PIANO KEY BALANCE

Alfred H. Howe, New York, N. Y.

Original application October 27, 1945, Serial No. 624,959. Divided and this application May 21, 1949, Serial No. 94,547

4 Claims. (Cl. 84—435)

1

This invention relates to a piano key balance or mounting.

The present invention is a division of the subject matter disclosed in my United States Patent No. 2,482,619 granted to me September 20, 1949.

Among the objects and advantages of the present invention are the following: It enables piano keys to be conveniently and easily mounted and leveled. The keys are kept from wobbling. A minimum of material is removed from the keys to accommodate the balancing device, thereby assuring strong keys, aside from reinforcement of the keys provided by virtue of novel features of the invention. Wear on the parts is reduced to a minimum thereby assuring usefulness of the keys for a long time.

The nature of the invention and its distinguishing features and advantages will appear when the following specification is read in conjunction with the accompanying drawings, in which

Fig. 1 is a side elevational view of a piano key mounted or balanced in accordance with the present invention.

Fig. 2 is an enlarged fragmentary view partly in section and partly in elevation showing certain parts of the key balance.

Fig. 3 is a sectional view taken on the line 3—3 of Fig. 2.

Referring now more particularly to the drawing, it will be apparent there is shown a frame 10 having a center key rail 11. A key 12 is mounted on the rail in accordance with the present invention as follows.

Use is made of a triangular plate 13 formed of sheet metal, preferably stainless steel. A stud or pin 14 projects downwardly from the plate at the base. A steel ball 15 is secured to the plate 13 at the apex thereof. The plate 13 with its pin 14 and ball 15 constitutes a fulcrum for the key 12. The pin 14 has a force fit in a hole extending in the frame 10 and the rail 11. The plate 13 extends vertically upward in contact with the rail 11. The broad flat sides of the plate are disposed so as to parallel the longitudinal axis of the key.

The key 12 has a vertical opening 16 therein approximately midway between its ends. The opening 16 in shape substantially conforms to the shape of the plate 13. However, the dimensions of the opening 16 are greater than those of the plate in all respects. The opening 16 merges into a circular countersink 17 in the key at the top, and said opening extends through the bottom of the key. A wooden apertured

bushing 18 is placed in the countersink 17. A felt bushing 19 is arranged in the countersink over the bushing 18. An elongated metal plate or cleat 20 is arranged longitudinally of the key 12 on the top thereof, and is secured in place by screws 21. The cleat 20 has a central tapped hole 22 therein which receives an adjusting screw 23. The head of the screw 23 is above the cleat 20. The screw 23 has a rounded cavity 24 in its lower end which bears on the bushing 19 which latter in turn bears on the ball 15. Felt bushings 25 are secured to the key 12 and extend over the opposite sides of the opening 16. The bushings 25 lightly contact the opposite sides of the plate 13.

The key 12 having the parts mentioned above is arranged to receive the plate 13. The bushing 18 steadies the ball 15, and the felt bushing 19 is interposed between the ball 15 and the screw 23 to reduce wear on the ball and screw, and to eliminate noise, especially in glissando playing. The screw 23 serves for leveling the key as balanced or fulcrumed on the ball 15. The bushings 25 help to steady the key, and since they bear on relatively large surfaces, the bushings 25 will endure long wear.

The use of a thin metal element, such as the plate 13, makes it necessary to remove only a minimum material from the key leaving the key strong. The use of the metal cleat 20 which carries the leveling screw 23 reinforces the key. The key may be manipulated easily without producing any extraneous sounds.

It is to be understood that although the bushing 19 is interposed between the ball 15 and the screw 23, the lower end of the screw may be said to bear on the ball 15 in construing the claims; and that minor changes may be made without departing from the spirit of the invention as defined in the claims.

I claim:

1. The combination with a piano key having an opening extending therethrough from top to bottom, of a fixed plate projecting upwardly into said opening, said plate having a ball at the top thereof, and a screw mounted on the key and having a lower concaved end bearing on said ball, thereby fulcruming the key upon the ball.

2. The combination with a piano key having an opening extending upwardly from the bottom of the key to the top of the key and providing a countersink at the top of the key, of a fixed plate projecting upwardly into said opening, said plate having a ball at the top thereof, a wooden apertured bushing in said countersink to steady said

3

ball, and a leveling screw mounted on said key and having its lower end bearing on said ball, thereby fulcruming said key upon the ball.

3. In a piano, the combination with a balance rail, of a triangular plate having a downwardly projecting pin tightly fitting in a hole in said rail thereby securing the plate vertically disposed with the lower edge of the plate in contact with the rail, a key having an opening extending therethrough from top to bottom, said plate projecting into said opening, and coacting means on the plate and the key which fulcrum the key upon the apex of the plate.

4. In a piano, the combination with a balance rail, of a triangular plate having a downwardly projecting pin tightly fitting in a hole in said rail thereby securing the plate vertically disposed with the lower edge of the plate in contact with the rail, a key having an opening extending

4

therethrough from top to bottom, said plate projecting into said opening, a ball on the apex of said plate, and a screw mounted on said key and having its lower end bearing on said ball, thereby fulcruming the key upon the ball.

ALFRED H. HOWE.
